UNITED STATES PATENT OFFICE

147,025

DESIGN FOR PACKING FOR FRAGILE
ARTICLES

Ernest L. Shepard, Fairfield, Maine

Application October 12, 1945, Serial No. 122,803

Term of patent 14 years

(Cl. D58—12)

To all whom it may concern:

Be it known that I, Ernest L. Shepard, a citizen of the United States, residing at Fairfield, in the county of Somerset, State of Maine, have invented a new, original, and ornamental Design for Packing for Fragile Articles, of which the following is a specification, reference being had to the accompanying drawing, forming part thereof.

Fig. 1 is a perspective view of packing for fragile articles showing my new design, the packing being open, and,

Fig. 2 is a similar view thereof but showing the packing in its closed position.

I claim:

The ornamental design for packing for fragile articles, as shown.

ERNEST L. SHEPARD.
